UNITED STATES PATENT OFFICE

114,666

DESIGN FOR A HOUSING FOR AN AIR CONDITIONING EXPANSION COIL AND FAN

Harold B. Parker, Pratt, Kans.

Application August 4, 1938, Serial No. 79,090

Term of patent 14 years

To all whom it may concern:

Be it known that I, Harold B. Parker, a citizen of the United States, residing at Pratt, in the county of Pratt and State of Kansas, have invented a new, original, and ornamental Design for a Housing for an Air Conditioning Expansion Coil and Fan, of which the following is a specification, reference being had to the accompanying drawing, forming a part thereof.

Figure 1 is a bottom perspective view of a housing for an air conditioning expansion coil and fan embodying my new design; and

Figure 2 is a top perspective view thereof.

I claim:

The ornamental design for a housing for an air conditioning expansion coil and fan, substantially as shown.

HAROLD B. PARKER.
